UNITED STATES PATENT OFFICE.

EMIL TYDEN, OF HASTINGS, MICHIGAN.

METAL-REINFORCED VENEER PANEL.

1,935,924.

Specification of Letters Patent. Patented Aug. 20, 1912.

Application filed May 15, 1912. Serial No. 697,370.

To all whom it may concern:

Be it known that I, EMIL TYDEN, a citizen of the United States, residing at Hastings, in the county of Barry and State of Michigan, have invented new and useful Improvements in Metal-Reinforced Veneer Panels, of which the following is a specification, reference being had to the accompanying drawings, forming a part thereof.

10 The purpose of this invention is to provide an improved construction of panels made of a plurality of layers of veneer and designed especially for use in cabinet construction, either as panels, shelves or partitions, which, notwithstanding the thinness and certain resultant characteristics of the multiple-ply veneer structure, shall have adequate stiffness in all directions, and otherwise meet the requirements of the use indicated.

20 It consists in the elements and features of construction shown and described as indicated in the claims.

In the drawings:—Figure 1 is a perspective view of a panel embodying this invention. Fig. 2 is a plan view of a panel showing the opposite side from that shown in Fig. 1, and having a portion of the layers of veneer broken away in part. Fig. 3 is a section at the line 3—3 on Fig. 1. Fig. 4 is a perspective view of a piece of metal reinforce.

The panel shown in the drawing comprises exterior veneer layers, 1 and 2, whose grain extends in the same direction, being preferably that of the narrower dimension of the panel, which comprises a third intermediate lamina of wood having the grain transverse to that of the exterior veneers, 1 and 2, the grain of said intermediate lamina being therefore longitudinal of the panel, as shown.

A panel constructed of three layers with the grain arranged as described, which is the common construction for thin panels designed for insets, partitions or light shelving, is adequately stiff in the direction of the length of the grain of the surface veneers, because, first, of the stiffness of the wood in the direction of the length of the grain, and second and chiefly, because these two layers being spaced apart by the full amount of the thickness of the intermediate layer which is thicker than either of them,—that is, by the maximum distance possible with a given thickness of panel,—operate as the tension

members of a truss structure; but in the transverse direction,—that is, that of the grain of the intermediate lamina,—the advantage of the natural stiffness of the surface veneers in the direction of the length of the grain being lost, and the middle layer not affording in the direction of length of the grain the stiffness to the panel as a whole which the surface veneers afford in the direction of the length of their grain, as above described, by reason of their being spaced apart, the panel is not normally adequately stiff in the direction of the length of the grain of said intermediate lamina, but, 60 on the contrary, is quite easily bent or sprung in that direction, and indeed, can be quite easily broken by bending in that direction. To compensate for this deficiency, and at the same time preserve the finished appearance of the panel upon one surface, I provide metallic stiffeners, 4, each of which is a strip of sheet metal folded into channel form, preferably having one of the flanges, 4^a, wider than the other and furnished with 65 a multiplicity of short lugs, 4^b; at its edge which are folded transversely to the flange,—that is, cross-wise to the channel. The narrower flange, 4^c, is let into a saw kerf, 5, cut in the longitudinal edge of the 70 panel deep enough to receive said flange and of suitable width to receive it tightly, so that, in fact, the flange has to be driven into the kerf. By reason of the flange, 4^c, being wider than the flange, 4^a, which has the 75 lugs, said flange, 4^c, can be thus driven into the saw kerf, notwithstanding the projection of the lugs cross-wise of the channel, and after it has been thus driven into the full depth so that the portion of the thickness of the panel at one side of the saw kerf is fully entered into the channel to the bottom of the latter, the lugs, 4^b, are forced into the surface of the panel, cutting their way 80 through the outer veneer, 1, at that side and embedding themselves in the intermediate lamina, 3. By this means, the channel binder or reinforce, 4, is rigidly and permanently secured on the edge of the panel. Both longitudinal edges of the panel are furnished with such reinforce members.

It will be observed that by this construction, the panel is left with one surface presenting only the finished wood veneer to view, and such panels are by this means 85 adapted for use in any cabinet structure in which only one surface of the panel is ex-

teriorly presented, and for all interior shelving and partitions where a completely finished appearance of all surfaces is not essential; but by employing suitable metal, 5 the appearance is not materially marred by the binding for many purposes.

Preferably, in making the saw kerf, 5, I avoid cutting between the outer veneer and the intermediate lamina, and prefer to make 10 the kerf in the intermediate lamina, just inward of the junction plane of the interior lamina and the veneer. By this means, the edge of the veneer is allowed to retain the reinforcement of a thin layer of longitudinal 15 grain of the intermediate lamina, and is prevented from splitting at the edge.

I claim:—

1. A veneer panel comprising exterior layers of wood veneer having the grain in 20 the same direction, and an intermediate layer of wood having the grain transverse to that of the surface veneers, in combination with metal reinforces for the edges trans- 25 verse to the grain of the surface veneers, such reinforces consisting of sheet-metal channels having one flange inserted in the edge to be reinforced proximate to one of the surface veneers, and the other flange clenched upon the opposite veneer surface.

30 2. A veneer panel comprising exterior

layers of wood veneer having the grain in the same direction, and an intermediate layer of wood having the grain transverse to that of the surface veneers, in combination with metal reinforces for the edges 3 transverse to the grain of the surface veneers, such reinforces consisting of sheet-metal channels having one flange inserted in the edge to be reinforced proximate to one of the surface veneers, and the other 40 flange clenched upon the opposite veneer surface, said last-mentioned flange being provided with a multiplicity of lugs penetrating the veneer at that side.

3. A wood veneer panel comprising a 45 plurality of thin layers of wood having their grains crossing one another, in combination with metallic binding for the edges, consisting of metal channels having one flange inserted into the edge to be bound and the 50 other flange clenched upon one surface of the panel.

In testimony whereof, I have hereunto set my hand, at Chicago, Illinois, this 11th day of May, 1912.

EMIL TYDEN.
